US00D816688S

(12) **United States Design Patent** (10) **Patent No.:** **US D816,688 S**
Kim et al. (45) **Date of Patent:** **** May 1, 2018**

(54) **DISPLAY SCREEN OR PORTION THEREOF WITH GRAPHICAL USER INTERFACE**

(71) Applicant: **Samsung Electronics Co., Ltd.,**
 Suwon-si (KR)

(72) Inventors: **Minsun Kim**, Seoul (KR); **Sora Kim**,
 Seoul (KR); **Cheolhoon Kang**, Seoul (KR); **Gwangha Jeon**, Namyangju-si (KR); **Hankyung Jo**, Seoul (KR)

(73) Assignee: **SAMSUNG ELECTRONICS CO., LTD.**, Suwon-si (KR)

(**) Term: **15 Years**

(21) Appl. No.: **29/589,747**

(22) Filed: **Jan. 4, 2017**

(30) **Foreign Application Priority Data**

Aug. 26, 2016 (KR) 30-2016-0041879

(51) LOC (11) Cl. **14-04**

(57) **CLAIM**

The ornamental design for a display screen or portion thereof with graphical user interface, as shown and described.

DESCRIPTION

The FIGURE is a front view of a display screen or portion thereof with graphical user interface showing our new design.

The outer perimeter shown in broken line in the FIGURE depicts a display screen or portion thereof and forms no part of the claimed design.

1 Claim, 1 Drawing Sheet
